UNITED STATES PATENT OFFICE.

THOMAS E. WALKER, OF DETROIT, MICHIGAN, ASSIGNOR TO CRITTALL CASEMENT WINDOW COMPANY, OF DETROIT, MICHIGAN, A CORPORATION OF MICHIGAN.

DOORSILL AND WEATHER STRIP.

Application filed August 21, 1925. Serial No. 51,555.

To all whom it may concern:

Be it known that I, THOMAS E. WALKER, a citizen of the United States, residing at Detroit, in the county of Wayne and State 5 of Michigan, have invented certain new and useful Improvements in Doorsills and Weather Strips, of which the following is a specification, reference being had therein to the accompanying drawings.

10 This invention relates to a door sill and weather strip, and has special reference to that class of casement doors which ordinarily open inward and are made of metal frames having kick plates movable relative 15 to a sill saddle.

My invention aims to furnish a casement door with a novel weather strip embodying two sealing members, but adapted to exclude the elements with one sealing member forming 20 a trough to exclude rough elements and the other sealing member to exclude fine elements. These sealing members are adapted to cooperate with saddle members in positively sealing the bottom part of a door relative 25 to a saddle or sill. The saddle members cooperate in forming another trough and together with a weather bar cooperate to the extent of preventing any kind of matter from passing under the bottom of the door.

30 My invention further aims to provide a weather strip construction that is durable and highly efficient for the purpose for which it is intended, and the construction will be hereinafter specifically described and 35 then claimed.

Reference will now be had to the drawing wherein—

Figure 1 is a horizontal sectional view of the door, partly broken away to show the 40 weather strip and saddle construction, and

Fig. 2 is a vertical cross sectional view of the door and saddle.

In the drawing, the reference numeral 1 denotes a sill floor or other base provided 45 with a transverse groove 2, and in said groove and extending onto the sill 1 is a cement filler and retainer 3 for a polished cast bronze saddle 4. To further anchor the saddle 4 relative to the sill 1, the lower face 50 of the saddle has a longitudinal depending angle bar or anchor 5 which extends into the groove 2 and is retained therein by the cementitious material 3. On the upper face of the saddle are longitudinal parallel spaced 55 apart outer and inner sill members or ribs

6 and 7 respectively cooperating with the saddle in forming a trough 8.

Swingable above the saddle 4 is a door frame 9 that may have kick plates or may have glass panels extending to the bottom 60 rail 10 of the floor. The bottom rail includes a depending flange 11 and an upstanding flange 12. Suitably mounted on the upstanding flange 12, preferably by screws 13, is an overhanging bronze curved weather 65 bar 14 which overhangs the saddle member 6 in spaced relation thereto and forms somewhat of a hood at the outer side of the door frame.

Secured to the depending flange 11 by 70 screws 15, or other fastening means, is a retaining strip 16, and between this strip and the flange 11 is sandwiched a yieldable non-metallic weather strip 17 that may be made of rubber, durable felt, or any yieldable 75 material. This weather strip is adapted to contact with the inner face of the saddle member 7 and the top of the saddle 4, and form an air tight connection between the door frame and the saddle.

Attached to the upper face of the retaining strip 16 by rivets 18 or other fastening means is the edge 19 of a resilient metallic weather strip 20 that may be made of brass or a non-corroding material. This weather strip is disposed at an angle to the bottom rail 10 and has a substantially horizontal wiping portion 21 terminating in an angularly disposed lip 22. The substantially horizontal portion 21 of the weather strip 20 is adapted to wipe and frictionally contact 80 with the saddle member 6 so that the weather strip bridges the gap between the saddle member 6 and the bottom rail 10, thereby extending over and closing the trough 8 of 85 the saddle.

The angularly disposed lip 22 extends in proximity to the weather bar 14 and cooperates with said bar in excluding some elements from entering the trough-like configuration of the resilient metallic weather strip.

As the door is swung open, the metallic weather strip is adapted to ride over the saddle member 7 and when contacting with said saddle member be slightly flexed. This is in order that when the door is closed the resilient weather strip will be flexed and exert a pressure on the saddle member 6, so that the elements cannot pass between the 105 110

saddle member 6 and the resilient weather strip. Should for any unforeseen reason elements enter the trough 8, it is practically impossible for the elements to pass yieldable 5 weather strip 17, therefore the two weather strips cooperate in providing a positive seal between the bottom rail 10 and the saddle 4. Again, the resilient metallic weather strip affords sufficient pressure on the saddle member 6 to hold the door in a closed position 10 against accidental opening. With the trough 8 in the saddle 4, it is practically impossible for foreign matter to pass over the saddle or interfere with the upper surfaces of the 15 saddle members 6 and 7, because said surfaces are wiped by the resilient metallic weather strip each and every time the door is opened or closed.

With certain minor modifications my 20 weather strip may be applicable to various types of doors, and for this reason I do not care to confine my invention to any structural details other than defined in the appended claims.

25 What I claim is:—

1. The combination of a door having a depending flange, a retaining strip under said door and secured to the door flange, a resilient metallic weather strip attached to said 30 retaining strip and adapted to engage a sill, a yieldable weather strip mounted between said retaining strip and the door flange and adapted to engage the sill, and a weather bar carried by said door and overhanging said 35 resilient metallic weather strip.

2. The combination called for in claim 1, wherein said resilient metallic weather strip has a trough-like configuration and extends 40 beyond the outer side of the door and in proximity to said weather bar.

3. The combination called for in claim 1

wherein said resilient metallic weather strip is attached to the upper edge of said retaining strip and said yieldable weather strip depends therefrom.

45 4. The combination with a sill and a door, of a saddle mounted on said sill and providing inner and outer sill members, a resilient metallic weather strip carried by said door and frictionally engaging the outer sill member, a yieldable weather strip carried by said door and engaging the inner sill member, and a weather bar on said door overhanging said resilient metallic weather strip.

50 5. The combination with a sill and a door, of a saddle mounted on said sill and providing inner and outer sill members, a resilient metallic weather strip carried by said door and frictionally engaging the outer sill member, a yieldable weather strip carried by said door and engaging the inner sill member, and a bottom rail for said door angular in cross section and providing a depending flange with said weather strips anchored in the angle of said bottom rail and the yieldable weather strip extending below 55 said depending flange.

60 6. The combination of spaced apart sill members, a swingable door bottom rail, a resilient weather strip carried by said bottom rail and extending outwardly from under 70 said bottom rail and adapted to be sprung in riding over one sill member to frictionally engage the other when said door is swung to a closed position, and another weather strip carried by said bottom rail and brought into engagement with the other sill member when 75 said door is closed.

In testimony whereof I affix my signature.

THOMAS E. WALKER.
